MILK BOTTLE COLLAR

Application filed February 26, 1930. Serial No. 431,397.

This invention relates to advertising devices, and has for an object the provision of a novel type of advertising device particularly adapted to be placed upon the neck of a conventional milk bottle, and to bear upon its face, suitable advertising matter.

A more detailed object is the provision of an advertising device in the form of a flat strip of flexible material—preferably paper—adapted to be bent to substantially circular configuration, and provided with means for securing the ends together, whereby the device may be disposed upon the neck of a conventional milk bottle.

A still further object is to provide the device with a novel clasp for attaching the ends thereof together in overlapping relationship and inclined angularly downwards, whereby the effective diameter of the upper portion of the device is reduced, and that of the lower portion is increased, with the result that the device is shaped to conform itself nicely to the tapering neck of a milk bottle.

A still further object is to provide an advertising device as described, which is of an exceedingly simple nature, both the strip and the clasp therefor being adapted to be formed of light-weight paper, and yet with the clasp so designed that it is possessed of a sufficient degree of rigidity to securely hold the parts in assembled relationship.

The invention possesses other objects and advantageous features, some of which, with those enumerated, will be set forth in the following description of the invention's particular embodiment which is illustrated in the drawings accompanying and forming a part of the specification.

Referring to the drawings:

Figure 1 is a side elevation of the neck of a conventional milk bottle, with a collar constructed in accordance with the principles of the present invention, supported thereupon.

Fig. 2 is a plan view of the collar in flat position, i. e., with the ends disengaged and the collar unrolled.

Fig. 3 is an edge elevation, the direction of view being indicated by the arrow 3 of Fig. 2.

Fig. 4 is an enlarged transverse sectional

view, the plane of section being indicated by the line 4—4 of Fig. 1, and the direction of view by the arrows. This view shows the manner of interengagement of the clasp portions of the device. Portions of the figure are broken away to reduce its length.

Fig. 5 is a transverse, vertical sectional view taken upon the line 5—5 of Fig. 2, with the direction of view as indicated, and with portions of the figure broken away to reduce its size.

Fig. 6 is a transverse sectional view taken upon the line 6—6 of Fig. 2, with the direction of view as indicated. Portions of this figure also are broken away to reduce its length.

Fig. 7 is a perspective view showing the manner whereby interengagement of the two ends of the strip is effected. Only the ends of the strip are shown, the remainder of the figure being broken away to reduce its size.

In terms of broad inclusion, the device of the present invention is a flexible strip of suitable material adapted to have advertising matter printed or otherwise placed thereupon, and provided with means for securing the two ends of the strip together so as to hold the device in substantially circular configuration whereby it may be inserted over the top of a milk bottle of conventional design. In its preferred embodiment, the advertising collar of the present invention, is in the form of a flat strip 11 of suitable flexible material. I prefer to employ paper for this purpose however, because of its cheapness and its adaptability for the reception of printing, whereby the collar may be enabled to carry appropriate advertising matter.

The top edge 12 of the strip 11 is preferably straight, whereas the bottom edge 13 is defined by two straight edges 14 converging to a point 16 midway between the ends 17 of the strip, with the result that the widest portion of the strip is at its center.

A slot 18 is formed adjacent one of the ends 17 of the strip, this slot being inclined downwards and toward the associated end 17, preferably at about 45°. A second slot 19, shorter than the slot 18, perpendicularly bisects the slot 18, the second slot 19 extending

in a direction toward the point 16 of the strip. Hence the slots 18 and 19 cooperate to define two opposed corners 21 at the inner edge of the slot 18, which may easily be deflected to facilitate entrance of the tongue 22 which is struck up from the strip 11 adjacent the other end thereof.

This tongue 22 is defined by a pair of intersecting slots 23, with the result that the tongue 22 is triangular in shape. Preferably the two slots 23 are of the same length, with the result that the shape of the tongue 22 is that of an isosceles triangle. Furthermore, the tongue 22 is so positioned that its apex 24 points downwards and away from the end 17 thereof adjacent. In other words, the base of the triangle which is defined by a line 25 joining the separated ends of the two slots 23, inclines downwards and toward the adjacent end 17 of the strip 11. The extent of the inclination here also is preferably substantially 45° . A short slot 26 extends inwards from the end of each slot 23, along the line 25.

25 A crease 27 is formed in the tongue 22, extending longitudinally thereof, i. e., the crease 27 lies on a line corresponding to the altitude of the triangular tongue 22, extending from the apex 24 to the base 25, midway between the ends of the latter. The effect of this crease 27 is two-fold, inasmuch as it serves to impart additional rigidity or stiffness to the tongue 22, and it also tends to make the tongue 22 extend angularly from the plane of the material of the strip 11 immediately surrounding the tongue 22, thus positioning the point or apex 24 thereof, at a point offset from the strip far enough to facilitate entrance thereof into the slot 18.

30 40 when the strip 11 has been bent to substantially circular configuration, wherein the ends 17 are in overlapping relationship.

The slot 19 which is perpendicular to the slot 18, also facilitates causing the tongue 22 to enter the slot 18, inasmuch as its presence adds materially to the flexibility of the material of the strip along the inner edge of the slot 18—that is to say, the corners 21 may easily be deflected from the plane of the material immediately surrounding the slot 18, toward the side thereof opposite that against which the other end 17 is lying. Obviously, this materially increases the effective width of the slot 18, whereby the operator is aided in causing the point 24 to enter the slot 18, as will readily be understood.

After the point 24 has passed through the slot 18, the two ends 17 should be pulled apart in a direction substantially tangential in respect to the circle described by the rolled collar, so as to slide the tongue 22 completely through the slot 18. This can be done only by swinging the ends 17 of the strip downwards into a position of angularity in respect 65 to each other as illustrated clearly upon

Fig. 1. This is due to the angularity of the slot 18 and of the base 25 of the tongue.

When the tongue 22 has been slid all the way through the slot 18, the short slots 26 also will come into register with the slot 18, whereupon one of the ends of the slot may enter the adjacent short slot 26, and thus securely interlock the tongue 22 within the slot 18.

The effect of swinging the ends 17 of the collar downwards into angularity with each other, is to decrease the diameter thereof at its top, and to increase its diameter at the bottom, whereby the collar is shaped in such a manner that it fits nicely upon the neck 31 of a conventional milk bottle 32. Moreover, the presence of the short slots 26, tends to prevent withdrawal of the tongue 22 from the slot 18, as would probably occur in the absence of the slots 26, due to the resilience of the material of the strip 11 which tends to cause the strip to assume a flat position, and hence continually exerts a force tending to pull the ends 17 thereof apart. Obviously, the engagement of one end of the slot 18 within the adjacent short slot 26, will retain the associated side of the tongue 22 against withdrawal. The other side of the tongue 22 is held within the slot 18 as a result of the fact that the associated extreme outer corner of the tongue becomes bent from the plane of the remainder of the tongue, whereby it is caused to become hooked over the outermost edge of the slot 18, preventing withdrawal of the associated side of the tongue. The small extent of bending of the corner of the tongue, necessary to effect such interengagement, is practically always effected without requiring the operator to devote any attention thereto, inasmuch as the ordinary handling of the strip necessary to interengage its ends, will produce the necessary amount of bending of the corner. As a result of such engagement of the two ends 17 of the strip, they are attached to each other at two spaced points, preventing not only withdrawal of the tongue 22 from the slot 18, but also preventing rotary movement of the ends in respect to each other, consequently holding the collar in conical configuration.

While it should be understood that the collar is equally adaptable for use upon tapering portions of various other articles, it has been designed primarily for use in conjunction with the conventional milk bottle, because of its adaptability as an advertising medium when so used. It is intended that a plurality of the collars be made up with their ends 17 joined as above described, and owing to their substantially frusto-conical configuration, a large number of the collars may be stored in a comparatively small space by resting them one upon another. Hence, a deliveryman may be supplied with a plu- 12

rality of the collars, enabling him to slip a collar upon the neck 31 of each of the milk bottles 32 as he effects delivery thereof, such placing of each collar being effected substantially instantaneously.

It is obvious therefore, that by employing this type of advertising matter, a dairy is enabled to inform its customers of new products handled thereby, or changes in prices, or business policy, as well as advertising its standard commodities; and the advertising medium is of such a nature that it is almost certain to command the attention of each customer to whom a bottle of milk is delivered.

It is to be understood that the details of the invention as herein disclosed, are subject to alteration within the spirit or scope of the appended claims.

20 I claim:

1. A collar for the neck of a container, comprising a flexible strip adapted to encircle said neck, one end of said strip having a slot therein and a tongue on the other end of the strip receivable in said slot to join said ends, said tongue extending in a direction rearwardly from the proximal end of the strip.

2. A collar for the neck of a container, comprising a flexible strip adapted to encircle said neck, one end of said strip having a slot therein, a tongue on the other end of the strip receivable in said slot to join said ends, said tongue extending in a direction rearwardly from the proximal end of the strip, and means for stiffening said tongue.

3. A collar for the neck of a container, comprising a flexible strip adapted to encircle said neck, one end of said strip having a slot therein and a tongue on the other end of the strip receivable in said slot to join said ends, said tongue extending in a direction away from the proximal end of the strip and having a crease extending longitudinally thereof to stiffen the tongue.

4. A collar for the neck of a container, comprising a flexible strip adapted to encircle said neck, one end of said strip having a slot therein inclined downwards and toward the end of the strip associated therewith, and a tongue on the other end of the strip inclined downwards and rearwardly from the end of the strip associated therewith.

5. A collar for the neck of a container, comprising a flexible strip adapted to encircle said neck, one end of said strip having a slot therein inclined downwards and toward the end of the strip associated therewith, a tongue on the other end of the strip inclined downwards and away from the end of the strip associated therewith, and means for stiffening said tongue.

6. A collar for the neck of a container, comprising a flexible strip adapted to en-

circle said neck, one end of said strip having a slot therein inclined downwards and toward the end of the strip associated therewith, and a tongue on the other end of the strip inclined downwards and away from the end of the strip associated therewith, said tongue having a crease therein extending longitudinally thereof to impart additional stiffness thereto.

7. A collar for the neck of a container, comprising a flexible strip adapted to encircle said neck, one end of said strip having a slot therein inclined downwards and toward the end of the strip associated therewith, and a triangular tongue on the other end of the strip inclined downwards and rearwardly from the end of the strip associated therewith.

8. A collar for the neck of a container, comprising a flexible strip adapted to encircle said neck, one end of said strip having a slot therein inclined downwards and toward the end of the strip associated therewith, and a triangular tongue on the other end of the strip inclined downwards and away from the end of the strip associated therewith, said tongue having a crease therein extending along a line perpendicular to the base and intersecting the apex thereof.

9. A collar for the neck of a container, comprising a flexible strip adapted to encircle said neck, one end of said strip having a slot therein inclined downwards and toward the end of the strip associated therewith, and a tongue on the other end of the strip inclined downwards and away from the end of the strip associated therewith, said tongue being defined by slots in said strip extending completely about said tongue except at the base thereof, and having a slot extending inwards from each side thereof at its base.

In testimony whereof I have signed my name to this specification.
